SPINNING TOP WITH ATTACHED FLEXIBLE
BALL CHAIN MEMBER

Joseph T. Radovan, Long Island City, N. Y.

Application August 13, 1948, Serial No. 44,050

2 Claims. (Cl. 46—70)

1

This invention relates to toy tops.

It is an object of the present invention to provide a connection of a cord or line with the top such that the top can be rotated with respect to the end of the cord and so that when the top has completed its spinning action, it can be lifted from the surface without having to bend over and likewise by the use of this cord control of the top can be had so as to prevent the same from entering spaces where it would be hard to retrieve the same.

Other objects of the present invention are to provide a top with a cord connected to the same wherein the connection is of simple construction, permits rotation of the top free of the cord, inexpensive to manufacture and efficient in operation.

For other objects and for a better understanding of the invention, reference may be had to the following detailed description taken in connection with the accompanying drawing, in which

Fig. 1 is a perspective view of the top having the cord connected thereto and embodying the features of the present invention, and with the cord retained in the hand of the boy who has operated the top.

Fig. 2 is a perspective view of the top, enlarged, and of the cord connected thereto.

Fig. 3 is a sectional view, in elevation, taken on line 3—3 of Fig. 2.

Fig. 4 is a perspective view of the retaining member for the top and its connection with the cord wherein the cord being connected to a ball chain which is in turn connected to the top body by the retaining member.

Referring now to the figures, 10 represents a top body having a small supporting point 11 on which the spinning action of the top is effected. In the top of the body is an opening 12 adapted to receive a fastening element 13 of a ball chain 14. The opposite end of the ball chain 14 has a fastening element 15 to which cord 16 of sufficient length to reach the boy's hand, is attached. The cord 16 is knotted as indicated at 17 to fit within the fastener 15. The opposite end of the cord 16 may also be knotted as indicated at 18.

In order to retain the fastener 13 within the opening 12, there is provided a retaining element or ferrule 19, Fig. 4. This ferrule has a central opening 20 and is dished so that its side flanges 21 fit over an upwardly extending projection 22 on the top of the body 10. The flange 21 has depending projections 23 adapted to enter the body

2

10 so that the ferrule will be fixed thereupon and against vertical displacement.

The diameter of the hole 20 is such that the fastener element 22 will be retained within the ferrule.

The top can be used in the usual manner by winding the cord 16 about the same. Upon a pull of the cord, the top will be spun and the cord will be made free of the top body. The top body 10 will revolve freely on the ball chain. The fastener 13 lies free in the opening 12 and it too may revolve within the opening. With the cord 16, the top when it comes to rest or at any other time, can be lifted by the cord 16 without having to bend for it. The top can be sold free of the cord and the cord simply inserted within the fastener 13, the cord being supplied by the user.

It should now be apparent that there has been provided a control cord for a top body which 20 does not interfere with the operation of the top once it had been started by the cord and whereby the top can be kept from moving to places where it would be hard to retrieve the same.

While various changes may be made in the detail construction, it shall be understood that such changes shall be within the spirit and scope of the present invention as defined by the appended claims.

Having thus set forth and disclosed the nature 30 of my invention, what is claimed is:

1. A spinning top comprising a top body, said top body having a pointed end upon which the body is rotated, said top body having an opening in the upper end, a raised portion about the opening, a flexible ball chain, a retaining member having a depending flange adapted to surround the raised portion about the opening, said retaining element having a central opening for rotatably receiving and retaining the ball chain, 35 said retaining member having depending projections extending into the top body for fixing the same thereto, a fastener element on the outer end of the ball chain, and a cord detachably connected to the fastener element.

2. A spinning top comprising a fibrous body having a pointed end upon which the body is rotated; a raised boss formed centrally upon the top of said body; an upwardly opening bore formed in the top of said body; a flexible ball chain member having a fastener element secured 50 to each of the opposite ends thereof; and a retainer member including an apertured disc through which said chain rotatably extends and adapted to retain one of said fastener elements, 55 a depending annular flange formed on said disc

for engagement over said boss with said one of said fastener elements being loosely disposed in said bore, and toothed projections on said flange extending into said fibrous body for rotatably securing said chain to said body.

JOSEPH T. RADOVAN.
